UNITED STATES PATENT OFFICE.

HERMAN KNEPPER, OF NEW YORK, N. Y.

DESIGN FOR A CLASP-BODY.

SPECIFICATION forming part of Design No. 31,939, dated December 5, 1899.

Application filed November 10, 1899. Serial No. 736,548. Term of patent 7 years.

To all whom it may concern:

Be it known that I, HERMAN KNEPPER, a citizen of the United States, and a resident of New York, borough of Manhattan, State of New York, have invented and produced a certain new and useful Design for a Clasp-Body, of which the following is a specification, reference being had therein to the accompanying drawings, in which—

10 Figure 1 is a perspective of the clasp-body; Fig. 2, a side elevation, and Fig. 3 a plan view thereof.

The clasp-body is formed from a single strip of narrow thin material *d*, bent upon itself midway its ends to form a U-shaped loop *a*, the ends of the strip being brought near to and parallel with each other and forming the straight untoothed jaws *e*. The sides of the loop at a point substantially midway of its 15 ends are curved inward toward each other, as at *b*. The closed end of the loop *a* is rounded outward from the adjacent ends of the inward-curved portions, as at *c*, and the strip

d, between the jaws *e* and the adjacent ends of the inward-curved portions *b*, are curved outward, as at *f*. From the two longitudinal edges of one arm of the loop *a* parallel lugs *g* extend at right angles to said arm, said lugs extending toward and a suitable distance beyond the other arm of the loop, said other arm lying between the lugs and having formed in its longitudinal edges notches *i*, in which said lugs fit. Perforations *h* are formed in the ends of these lugs, and said lugs are formed on the arm of the loop *a* at substantially the 25 innermost point of the inward-curved part *b*.

I claim—

The design for a clasp-body substantially as shown and described.

In testimony whereof I hereunto affix my 30 signature, in the presence of two witnesses, this 6th day of November, 1899.

HERMAN KNEPPER.
